United States Patent Office

Des. 175,523
Patented Sept. 6, 1955

175,523

DICTATION MACHINE

Emil C. Steinbach, Chicago, Ill., assignor to
Charles P. Peirce, Wilmette, Ill.

Application March 8, 1954, Serial No. 29,407

Term of patent 7 years

(Cl. D26—14)

Fig. 1.

Fig. 2.

Fig. 3.

Figure 1 a front perspective view of a dictation machine showing my new design;

Figure 2 is a rear perspective view; and

Figure 3 is another rear perspective view showing the opposite side of the machine from that shown in Figure 2.

I claim:

The ornamental design for a dictation machine, substantially as shown.
